DESIGN FOR A SHOE

Harry Le Roy Sutcliffe, New York, N. Y.

Application September 22, 1941, Serial No. 103,453

Term of patent 3½ years

To all whom it may concern:

Be it known that I, Harry Le Roy Sutcliffe, a citizen of the United States of America, residing in New York city, county of New York and State of New York, have invented a new, original, and ornamental Design for a Shoe, of which the following is a specification, reference being had to the accompanying drawing, forming part thereof.

Fig. 1 is a plan view of a shoe showing my new design.

Fig. 2 is a side elevational view thereof.

The dominant feature of the design is shown in full lines.

I claim:

The ornamental design for a shoe, substantially as shown and described.

HARRY LE ROY SUTCLIFFE.
